Primary Examiner — Mehri F Bajoul

(57) **CLAIM**

The ornamental design for a game controller, as shown and described.

DESCRIPTION

FIG. 1 is a perspective view of a game controller showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the game controller shown in a configuration of use; and,

FIG. 10 is an enlarged view of portion 10 shown in FIG. 1. The even dash-dash broken lines on the game controller depict portions that form no part of the claimed design. The even dash-dash broken lines showing of a right hand game controller in FIG. 9, depict environmental structure. The long-short dash lines in FIGS. 1 and 10 depict bounds of magnified portion and form no part of the claimed design.

1 Claim, 10 Drawing Sheets
